UNITED STATES PATENT OFFICE.

GEORGE H. McDOLE, OF JACKSON, MICHIGAN, ASSIGNOR OF ONE-HALF TO
HOWARD L. MERRIMAN, OF SAME PLACE.

TRACE-COCKEYE ATTACHMENT.

SPECIFICATION forming part of Letters Patent No. 292,171, dated January 22, 1884.

Application filed August 31, 1883. (No model.)

To all whom it may concern:

Be it known that I, GEORGE H. McDOLE, a citizen of the United States, residing at Jackson, in the county of Jackson and State of Michigan, have invented certain new and useful Improvements in Trace-Cockeye Attachments, of which the following is a specification, reference being had therein to the accompanying drawings.

10 This invention has relation to improvements in attachments for trace-cockeyes; and it consists in providing a plate that is interposed between the end of the trace and the cockeye, all as will be hereinafter more fully explained, 15 and particularly pointed out in the claim appended.

The annexed drawings, to which reference is made, fully illustrate my invention, in 20 which Figure 1 represents a face view of my device, and Fig. 2 is a vertical sectional view of the same.

Referring by letter to the accompanying drawings, A designates a metal plate, the rear end, a, of which is provided with a projection, 25 b, which is transversely perforated, as at c, to receive the screw-bolt d, by means of which the cockeye e is connected or hinged to the rear end of said plate. The plate A is provided on its face with a projecting stud or 30 hook, f, that is arranged about midway its length, which engages the slot g in the end of the trace h, which latter passes through the loop i at the forward end of the plate, as shown in the drawings. Said loop is formed by the 35 side bars, k k, which are curved upwardly and

forwardly, and connected by a transverse bar, m, and the plate aforesaid is cut away at its forward end between the side bars. Said plate is further provided with notches n n on each side of the stud, to admit the operator's thumb 40 and finger in releasing the trace from the stud when it is desired to separate the trace from the plate.

It will thus be seen by reference to the drawings that the plate with the cockeye can be 45 readily detached from the trace when it is desired to attach the latter only to the whiffletree, as there is no riveting or stitching of these parts. At the same time it is cheap to manufacture. 50

Having described my invention, what I claim, and desire to secure by Letters Patent, is—

The herein-described trace-cockeye attachment, consisting of the plate A, having the 55 loop m at one end and the solid projection b at its opposite end, and transversely perforated to receive the bolt d of the cockeye, said plate provided with the tongue f, centrally arranged thereon to receive the eye in the trace h, and 60 having in its sides notches n n, in combination with a cockeye, all arranged and operating substantially as shown and described.

In testimony whereof I affix my signature in presence of two witnesses.

GEORGE H. McDOLE.
